UNITED STATES PATENT OFFICE.

JOHN I. HOKE, OF SOUTH BEND, INDIANA.

SULKY-PLOW.

SPECIFICATION forming part of Letters Patent No. 257,327, dated May 2, 1882.

Application filed February 14, 1882. (No model.)

To all whom it may concern:

Be it known that I, JOHN I. HOKE, of South Bend, in the county of St. Joseph and State of Indiana, have invented certain new and useful 5 Improvements in Sulky-Plows; and I do hereby declare that the following is a full, clear, and exact description thereof, reference being had to the accompanying drawings, and to the letters of reference marked thereon, which form 10 part of this specification, in which—

Figures 1 and 2 are reverse side elevations. Fig. 3 is a rear view; Fig. 4, a view of the cam-lever; Fig. 5, a view of the sliding axle, and Fig. 6 a view of the stirrup.

This invention relates to improvements on sulky-plows; and the nature of my invention consists, first, in combining with the short axle of the land-wheel, which is adjustable on one of the arms of the arched axle, a flanged cam 15 having a hand-lever on it, an anti-friction roller, and a lip formed on the adjustable sleeve of the said short axle, as will be hereinafter explained, whereby the attendant can level the frame, whether the machine be plowing or on a 20 level road; second, in a novel method of suspending the plow and the rear part of its beam from a vertically-adjustable bail, in combination with a suspension-stirrup, which is free to travel laterally and to vibrate on said bail, 25 and a suspension-spring on which the rear part of the plow-beam is sustained, which spring is rigidly secured at one end on top of said beam, 30 as will be hereinafter explained.

The following description of my invention 35 will enable others skilled in the art to understand it.

A, A' designate two transporting-wheels, which are applied to an arched axle, B. The largest wheel, A, is designed to run in the furrows, and the smaller wheel, A', is designed to 40 run on the unplowed ground. Both of these wheels may be of the same diameter. The short axle C of wheel A' has a square sleeve, C', and a stud, a, and also a lip, b, formed on it, as shown in Fig. 5. The sleeve C' receives 45 freely through it the vertical arm of the arched axle B. The stud a has applied on it an anti-friction roller, c, and between this roller and the overhanging lip b the flange e of a cam, D, is received and allowed to play longitudinally 50 with respect to the length of the machine. The cam D and its hand-lever D' have their ful-

crum at f on the left-hand end of the arched axle B. By this combination of devices the driver, while in his seat on the machine, can 55 raise or depress the land-side end of the latter, and thus level the axle, whether the machine be plowing or moving on level ground.

It will be seen that by means of the lever-cam I take hold of the land-side axle without 60 the interposition of a second lever or link, and hence the expenditure of very little manual power is required on the part of the driver in leveling the machine.

E designates a short longitudinal beam, which 65 is centrally secured to the arched axle B at its rear end and braced rigidly to this axle by means of the angular frame F, and also by means of a brace, F', which latter extends a short distance back of the landside and has 70 pivoted to it one end of a bail, G. The opposite end of this bail is pivoted to the angle of a toothed segment, H, secured rigidly to that end of the arched axle bearing the furrow-wheel A. A lever, G', which is an upward extension and integral part of the bail G, is used 75 for adjusting this bail up or down. By means of a latch, h, applied to the hand-lever G' this lever can be engaged with segment H and the bail held rigidly at any desired height. 80

I will here state that the hand-lever D' of cam D is provided with a latch, i, adapted to engage with a toothed segment, D'', on the axle B, and to hold the same at any desired 85 height or level.

The front end of the beam E receives vertically through it a swivel furcated pin, j, between the lower ends of which the plow-beam J is pivoted. This attachment allows the plow-beam, which carries a plow of suitable construction, to receive free lateral and vertical movements. I have not represented means for attaching a double-tree to the plow-beam clevis, as this may be done in a variety of ways, and I make no claim thereto. 95

K designates a stirrup, through the lower part of which the plow-beam passes loosely just over the plow. This stirrup is twisted, as shown in Fig. 6, and it is hung from the transverse part of the bail G by means of a roller, 100 k, having a concave periphery. This stirrup K is allowed to vibrate laterally and longitudinally and to traverse the bail-rod.

S designates a flat spring, which is rigidly

secured at its front end to the plow-beam. The free rear end of this spring crosses a pin, *n*, which passes through the stirrup over the plow-beam, and when the plow is in operation the 5 spring bears on said pin *n*, and by the yielding movement allowed the point of the plow will run at an even depth in the soil, notwithstanding the land-side wheel may travel over inequalities of surface.

10 The elongated bail *G* allows the sulky to turn in either direction without disturbing the position of the plow in the ground.

Having described my invention, I claim—

15 1. In a sulky-plow, the short land-side axle *C*, constructed with a sleeve, *C'*, a stud, *a*, and a lip, *b*, in combination with the arched axle *B*, anti-friction roller *c*, cam *D*, its lever *D'*, and a locking device therefor, substantially as and for the purposes described.

20 2. The combination of the sleeve *C'*, bearing

the short axle *C*, and adjustably applied on the vertical limb of the arched axle, with a lever having a flanged cam on its end adapted to engage with sleeve *C*, for leveling the machine, substantially as described.

25 3. The combination of the pivoted bail, its hand-lever and locking device, the arched axle, the plow-beam pivoted vertically and horizontally at its front end to the sulky-frame, the suspension-stirrup for this beam, adapted to 30 ride on said bail, and the suspension-spring *S*, having a bearing, *n*, on the stirrup, substantially as described.

In testimony that I claim the foregoing as my own I affix my signature in presence of 35 two witnesses.

JOHN I. HOKE.

Witnesses:

JAMES DU SHANE,
ANDREW ANDERSON.
